(57) **CLAIM**

We claim the ornamental design for a hummingbird feeder, as shown and described.

DESCRIPTION

FIG. 1 is a top perspective view of a hummingbird feeder according to the first embodiment of the present design with a flower shaped feeder port displayed in one of the three access holes;

FIG. 2 is a top plan view of the FIG. 1 embodiment;

FIG. 3 is a front elevation view of the FIG. 1 embodiment;

FIG. 4 is a left elevation view of the FIG. 1 embodiment; the right elevation view being a mirror image thereof;

FIG. 5 is a rear elevation view of the FIG. 1 embodiment;

FIG. 6 is a bottom plan view of the FIG. 1 embodiment; and,

FIG. 7 is a sectional view taken along Line 7—7 of FIG. 3.
